UNITED STATES PATENT OFFICE

TONY T. TUCZYNSKI, OF MILWAUKEE, WISCONSIN.

REFRIGERATOR.

1,182,819.

Specification of Letters Patent.

Patented May 9, 1916.

Application filed September 18, 1913. Serial No. 790,510.

To all whom it may concern:

Be it known that I, TONY T. TUCZYNSKI, a citizen of the United States, residing at Milwaukee, in the county of Milwaukee and State of Wisconsin, have invented certain new and useful Improvements in Refrigerators; and I do hereby declare the following to be a full, clear, and exact description of the invention, such as will enable others skilled in the art to which it appertains to make and use the same.

This invention relates to refrigerators and one of the principal objects of the same is to provide a refrigerator which will not require the use of ice and which can be maintained at low cost.

Another object of the invention is to provide a series of shelves for supporting the provisions, said shelves being formed of tubes or pipes through which cold water is adapted to pass out to the flush tank.

These and other objects and advantages may be attained by means of the construction illustrated in the accompanying drawings, in which—

Figure 1 is a front elevation of a household refrigerator made in accordance with my invention, Fig. 2 is a vertical sectional view of the same, Fig. 3 is a horizontal sectional view taken on the line 3—3 of Fig. 2, Fig. 4 is a detail sectional view showing the construction of one of the shelves and the plates at opposite sides of the pipes forming said shelves, and Fig. 5 is an enlarged detail view showing the manner of supporting one of the shelves at one side thereof.

Referring to the drawings the numeral 1 designates a household refrigerator casing with suitable doors 2, and a shelf 3 at one side thereof.

The construction of the refrigerator may be varied within great limits and as shown in Fig. 2 is provided with a lining 4. A drip tube 5 extends through the bottom of the refrigerator and is designed to catch the water of condensation from the pipe and pass it off as waste.

Leading from the water supply spigot of a sink 6 is a pipe 7, said pipe extending through one side of the refrigerator and having connected thereto a pipe 8 forming the upper member of a zigzag series of pipes 9 extending from near the top to the bottom of the refrigerator. Connected to the lower member 9 of the pipes is a vertical pipe 10 which extends out through the bot-

tom of the refrigerator and is provided with a horizontal connecting pipe 11 which leads to the water main. The water is forced up through the pipe system and out to be used at the sink 6 through the spigot 6^a and the surplus is passed through the pipe 12 to the flush tank 13, for a toilet bowl, (not shown) the water passing through the pipes 14 and 15 to said tank.

Connected to the pipe 7 is a fitting 16, to which is connected the horizontal series of pipes 17 forming the shelves. These pipes communicate with the vertical connections 18 and the shelves are each provided with top and bottom plates 19 placed upon opposite sides of the shelves and connected together by means of bolts 20. The top plates provide the shelves with smooth unbroken article supporting surfaces. The bottom plate of each shelf prevents water of condensation accumulating upon the series of pipes from dripping on articles located below the shelf, the water of condensation being conveyed by the plate to the sides of the provision chamber. For giving stability to the shelves and supporting them cross tubes or rods 21, supported at their ends by caps 22 secured to the walls of the refrigerator, are provided. These shelves communicate with the water supply pipe 11 through suitable connections and when the water is forced through the pipe to the sink and flush tank the refrigerator will be at a suitable temperature for keeping provisions and preventing deterioration.

My refrigerator is simple in construction, can be maintained at low cost and will save the usual great expense for ice.

What I claim is:—

1. A refrigerator provided with a provision chamber, a shelf located within the provision chamber and consisting of a horizontal series of pipes, a feed pipe communicating with the series of pipes, a discharge pipe communicating with the series of pipes, a top plate secured to the upper side of the series of pipes to provide the shelf with a smooth unbroken article supporting surface, and a bottom plate secured to the underside of the series of pipes to prevent water of condensation accumulating on the pipes from dripping on articles located below the shelf, said bottom plate being adapted to convey the water to the sides of the provision chamber.

2. A water cooled refrigerator comprising

a provision chamber, caps secured to the side walls of the provision chamber, cross rods having their ends secured in the caps, a bottom plate resting upon the cross rods, a 5 horizontal series of pipes resting upon the bottom plate, a feed pipe communicating with the series of pipes, a discharge pipe communicating with the series of pipes, a top plate resting upon the upper side of the 10 series of pipes, and securing means passing through the series of pipes and engaging the top and bottom plates, said top plate providing a smooth unbroken article sup-

porting surface, and the bottom plate being adapted to prevent water of condensation 15 accumulating on the pipes from dripping on articles located below the plate, and to convey the water to the sides of the provision chamber.

In testimony whereof I affix my signature 20 in presence of two witnesses.

TONY T. TUCZYNSKI.
